CONSTRUCTION OF SUBMERGED
STRUCTURES

John P. Emshwiller, Riverdale, Md.; Bertha J. Emshwiller, administratrix of said John P. Emshwiller, deceased, assignor to Bertha J. Emshwiller

Application April 6, 1949, Serial No. 85,921

10 Claims. (Cl. 61—46)

(Granted under Title 35, U. S. Code (1952),
sec. 266)

1

The invention described herein may be manufactured and used by or for the Government of the United States for governmental purposes without the payment to me of any royalty thereon in accordance with the provisions of the act of April 30, 1928 (Ch. 460, 45 Stat. L. 467).

This invention relates to underwater construction. Particularly the invention relates to a method for the construction of an underwater foundation and to the foundations so constructed.

Heretofore in order to construct underwater foundations capable of supporting large structures above the water and which structures are subjected to heavy lateral forces, it has been necessary to maintain relatively heavy equipment at the site during the period of construction of the caissons, cofferdams or cribs. Such operations involve risks to equipment or personnel due to the probability of storms occurring during the construction, over and above the risks involved by the construction itself, and are therefore expensive.

Accordingly, it is an object of this invention to provide a new method for the construction of underwater foundation capable of supporting large top side structures and highly resistant to lateral thrust without the use of cofferdams, caissons, cribs or divers at locations where the soil offers low resistance and necessitates the use of piles.

It is another object of this invention to reduce the risks of damage due to storms arising during the construction period by both shortening the time of construction and also by providing a method whereby operations can be stopped and the supplementary equipment can be returned to port during the storms without increasingly heavy losses in time or equipment and without jeopardizing the uncompleted construction.

It is another object of this invention to provide a foundation that will remain stable in the event that the soil is washed out from under the foundation, hereinafter referred to as scarring.

Other objects and advantages will be apparent or will appear hereinafter in the detailed discussion of the invention.

These objects and advantages are accomplished in accordance with this invention by the method of constructing an underwater foundation which comprises erecting structural supporting members integral with a water-tight shell which can be floated into position, submerging said shell by decreasing its buoyancy until it rests

2

at the desired position on the bottom, driving piles to a desired penetration through open end tubes which pass through said shell from skin to skin in a substantially vertical plane and which exclude water from said shell and interlocking the heads of said piles and said open end tubes.

In another embodiment of the invention these objects and advantages are accomplished in accordance with this invention by the method of 10 constructing an underwater foundation which comprises erecting vertical structural supporting members integral with a water-tight shell which can be floated into position, while said shell is substantially afloat partially driving vertical 15 guide piles through open end tubes which pass through said shell from its upper and lower planes; and which exclude water from said shell, submerging said shell and structural members by decreasing the buoyancy thereof until it rests 20 on the bottom; driving piles through said open end tubes to the desired penetration; and interlocking said piles and said open end tubes.

Reference is to be had to the accompanying drawings forming a part of this specification in 25 which similar characters of reference indicate corresponding parts in all views and in which—

Fig. 1 is a vertical section of a diagrammatic view of one completed embodiment of this invention.

30 Fig. 2 is a top view of a typical embodiment of the shell.

Fig. 3 is a vertical section of a diagrammatic view of one embodiment of the invention prior to the step of submerging the shell.

35 Fig. 4 is a vertical section of a diagrammatic view of one embodiment of the invention during the step of submerging the shell.

Fig. 5 is a sectional diagrammatic view of one embodiment of the invention showing pile driving using a removable follower and a method of 40 interlocking the pile head and pile tubes.

Figs. 6 to 9, inclusive, are sectional views of various embodiments of pile tube construction and interlocking.

45 The invention, however, is not to be construed as limited to the specific details shown in these drawings as they are merely representative of but a few of many embodiments of the invention.

50 Referring to Fig. 1, the completed foundation is shown wherein the water-tight structure or shell 10, known to the trade as an aquapad, supporting structural members 11 and superstructural members 111; piles 12 have been driven to a penetration which will give the desired sup-

port and resistance to overturning and lateral displacement. The piles 12 were driven in place through open end tubes (sometimes referred to as pile tubes) 13 which pass through the shell from skin 101 to skin 102. At the completion of the pile driving step the pile heads should be approximately in the center of the pile tube both laterally and vertically. This can be accomplished by the use of a removable pile follower as shown in Fig. 5, item 121. The pile heads 14 are shown as being interlocked with the pile tubes 13 by means of a grouting composition 15 such as concrete. Additional strength may be given to the entire structure by filling the shell 19 with concrete or other grouting composition, aggregate, or fill 16. Item 18 is a connection used for filling and discharging ballast during the submerging and seating operations, and hereinafter will be referred to as the ballasting connection. Items 17 are connections which can be used to fill the shell with concrete at the completion of the construction if desired, and hereinafter will be referred to as a utility connection.

The shell 10 can be of any desired shape to supply the proper foundation and support for the superstructure. A presently proposed shell is one such as is shown in Fig. 2, a cylindrical shell. The shell proper can be either a single shell or, in the case of exceedingly large units, it can be compartmented into water-tight sections; in such cases each section should have its own utility and ballasting connections 17 and 18. By this means the buoyancy of the entire unit can be more readily controlled to insure seating and maintaining it in the desired position.

As shown by Figs. 1, 3, and 4, the vertical structural members 11 and 111 which are to extend above the water line after completion can be of any design necessary to provide the desired support. They can be attached to the upper deck of the shell or can be integral with the shell interior and thereby benefit from the additional strengthening and stiffening imparted by the shell and fill.

Such units (the shell, pile tubes, and structural members) can be constructed in various ways. For a few examples: They can be built ashore and floated to the construction site; they can be built at the site and launched there; or in some instances, the vertical structural members can be erected on the floating shell at the site by the use of relatively light equipment.

The piles 12 can be of any desired material, type, or size to provide the required resistance. Preferably, the pile heads 14 should be deformed or irregular in order to provide a better interlock with the pile tubes 13, as will be discussed hereinafter. The deforming of the heads can be accomplished by various devices, a few of which are shown in Figs. 6 to 9 inclusive, or may be expanded, thus creating an irregular surface, in such manner as that shown in applicant's co-pending applications 160,201 and 160,202 or in any other manner.

Referring now to Figs. 6, 7, 8, and 9, which show a few of the many possible embodiments of the pile tubes 13, deformed pile heads, and other various structural details. The tubes can be of any shape or size sufficient to accommodate the selected piles and which provide sufficient volume to permit forming a strong interlock with the grouting composition. Figs. 1, 2, 3, and 4 indicate the use of cylindrical straight wall tubes; however, it is presently preferred to em-

ploy inverted conical or stepped tubes such as those shown in Figs. 5, 6, 7, 8, and 9, because such tubes in having a relatively wide upper opening 133 and a relatively narrow bottom opening 134 make it easier to locate and center the piles at the start of driving operations, and they permit the use of a wider variety of sealing means at the lower extremity 134. In preferred embodiments the walls or surfaces of the tubes are made irregular or deformed as illustrated in Figure 9, or by affixing to such surfaces angle irons as illustrated in Figures 6, 7, and 8. The desirability of having such irregularities both inside and outside the tubes should be noted, for they assure the rigid connection of the pile to the fill within the shell via the grouting around the piles and the tube walls and irregularities therein.

The pile tubes or open end tubes 13 pass completely through the shell 10 from its upper deck 101 to its lower deck 102 and are in a substantially vertical line. For most purposes they can be perpendicular to the bottom but as shown in Fig. 1, it is often convenient that they should be at an angle to the bottom to permit the use of batter or inclined piling 122. The pile tubes are installed in such a manner that they will exclude water from the interior of the shell. Such installation can be accomplished in various ways. For example, a flanged pile tube can be held in place by bolts, rivets, or the like, and water-tight integrity of the shell assured by gaskets or caulking; however, for reasons of economy, welding to the shell at points of penetration are preferred at present.

Another desirable embodiment is shown in Fig. 9 wherein the pile tube is formed in the shell concrete fill 16 prior to submergence.

For purposes of providing additional mechanical strength to the tube and shell during pile driving operations, it is often desirable to reinforce the pile tube by partially or completely filling the portions of the shell surrounding the pile tubes with reinforced concrete, or the like, such as shown in Figs. 3, 4, and 5.

Still another possible variation is shown in Fig. 6 wherein a cage or similar reinforcing 161 surrounds the pile tube to strengthen the shell concrete 16. When such practice is followed it is usually desirable to have deformities such as shown by item 131 in Figs. 6, 7, and 8 on the portions of the pile tube inside the shell; by such means additional locking surfaces are provided.

Fig. 6 shows a pipe pile 12 which has been driven to the desired penetration and having its head 14 approximately half way in the pile tube 13. The pile head 14 has welded rings 141 or other deformities such as angles, lugs, or the like, which aid in effecting the interlock with the pile tube 13 through the grout or concrete. The interior surface of the pile tube may also be deformed to effectuate the interlock as shown by items 132 of Figs. 6 to 9 inclusive. Since the pile tube is rigidly attached to the shell 10, the interlocking of the pile and pile tube will therefore serve to anchor the entire foundation to the bottom. The interlocking can be accomplished by filling the pile tube with concrete or other grouting composition 15 after completion of the pile driving and allowing it to set or harden.

This interlocking or "grouting-in" of the pile head can be accomplished merely by pumping the grout or concrete down to the pile tube, or by securing a pouring tube 20, which extends above the waterline as shown in Fig. 5, in the

upper portion of pile tube 133. After the pouring tube is in place, the gasket or sealing means (19, Fig. 7) can be packed tightly between the pile and pile tube sealing the lower opening 134; however, a slight seepage has not been found to be harmful. If desired, the water may be removed from the pile tube and pouring tube and a grout can then be introduced to interlock the pile head and pile tube.

Upon the setting of the pile tube grout, and when desired, filling of the shell with concrete or the like, by disconnecting the shell ballasting and utility connections and removing the pouring tube, the construction of the foundation is completed.

As shown in Fig. 1, item 30 a portion of the soil may become washed out from below the shell. By using this invention a structure will remain erect even in extreme cases of such scarring.

The following examples will show various methods by which the invention may be carried out but the invention is not to be construed as limited thereto.

Example I

Referring particularly now to Fig. 3 which shows the shell 10 and structural members 11 floating in the water near a tender 25. Vertical guide piles 12 are run through the open end pile tubes 13 and partially driven into the bottom. The buoyancy of the shell 10 is then decreased by adding ballast through the ballasting line 181 and its shell connection 18 while venting the shell through shell connection 17 and utility tube or line 171 extending above the surface. This will cause the shell and structural members to be submerged. The guide piles will assure proper positioning of the shell when it reaches bottom. Such practice is especially desirable when there is a current at the construction site which might cause a shifting of the shell during or after submergence. When the shell is on the bottom the pile driving operation can be completed by usual methods, making sure that when the desired pile penetration has been reached the pile head is substantially near the center of the pile tube both vertically and horizontally. The pile head and shell tube are then interlocked by grouting and the structure completed as has been previously described.

Example II

In some instances it is undesirable to use guide piles. In such instance the floating shell can be submerged prior to the driving of any piles to an approximate location on the bottom. The structure can then be brought into the desired position by increasing its buoyancy; i. e., removing ballast until it just floats free of the bottom. When in such a state the entire structure can be easily moved by relatively light equipment on an accompanying tender. The completion of the foundation is then carried out as heretofore described.

When there is a substantial current in the water, it may be necessary to secure lines to one or more barges upstream from the desired location of the foundation during the submerging operation. It has also been found helpful to drive two or more temporary piles in such manner as to constitute a fence on the down stream side of the desired location so that when the shell is near the bottom it can be permitted to be guided into position by such piles.

Example III

Another possible method of employing this invention is shown by Fig. 4. In this example the foundation is to be installed in relatively deep water; therefore it is impractical to attempt to maintain the stability of the shell and the tall superstructure 111 while it is being towed to the construction site. Fig. 4 shows that the shell 10 has been submerged as described in either Example I or II; and then by properly controlling the buoyancy and by using relatively light equipment 251 on the accompanying tender 25 the shell may be maintained in a submerged state at any depth, which permits additional vertical structural members 111 to be attached to a lower structural member 11 while its upper portions are above the waterline. If the shell connections 17 and 18 are substantially non-collapsible, the assembly of the shell and such connections gains buoyancy as the shell descends. It has been found that very accurate control of depth can be obtained with great ease by the operation of small ballast pumps. After the additional structural members have been added, buoyancy can then be decreased and the structure is sunk to the bottom, and the foundation can be completed as aforementioned.

From the foregoing description and examples it is apparent that this invention has provided a new method of the construction of underwater foundations and also a simplified type of submerged foundation.

While the invention as particularly described contemplates an uninterrupted operation, in many instances, such will not be the case; for example, storms may occur or equipment may fail. In such cases the shell may be sunk to the bottom by decreasing its buoyancy and stored there until operations can be resumed; at which time the shell may be refloated by increasing its buoyancy and operations continued in the normal manner. This is in distinct contrast to previous storm or mechanical failure procedures which subject the project to great hazards, which increase the costs and jeopardize personnel.

While the invention as particularly described shows the piles driven to depths whereby the pile and head are centered in the pile tube, the invention is not limited thereto and interlocks can be effected between piles whose heads are above the pile tube opening and the pile tube. Since many widely differing embodiments of the invention will occur to one skilled in the art, it is not limited to the specific details illustrated or described and various changes can be made therein without departing from the spirit or scope thereof.

60 What is claimed is:

1. A method of constructing underwater foundations that consists in constructing a substantially watertight buoyant shell having top and bottom and side walls and having pile receiving tubes extending therethrough and secured to said top and bottom walls; assembling superstructure elements on said shell; floating the assembly to the site of the foundation; decreasing the buoyancy of the assembly to sink it to the bottom; driving through said pile tubes and to a firm bearing in the bottom, piles that, when driven, have portions within said pile tubes of less diameter than the surrounding portions of the pile tubes; and introducing settable grouting material into the spaces thus left between the piles and

pile tubes to secure the submerged shell directly to the driven piles.

2. A method according to claim 1 further comprising the steps of building the shell with pile tubes having internal deformities presenting longitudinally acting abutments; providing the portions of the piles that when driven, will be within the pile tubes, with external deformities presenting longitudinally acting abutments; sizing the deformities in the pile tube to allow driving of the pile therewith; and sizing the deformities on the piles to be capable of entering the pile tubes, whereby setting of the grouting material introduced after driving of the piles through the tubes effects a longitudinally fixed interlock between the piles and pile tubes.

3. A method according to claim 1 further comprising the steps of reinforcing the pile tubes prior to driving of piles therethrough by building about them, internally of the shell, concrete reinforcing.

4. A method according to claim 1 further comprising the steps of building the pile tubes with external deformities presenting longitudinally acting abutments within the hollow shell, and casting concrete within said shell to form a monolithic body locked to said pile tubes irrespective of later deterioration of the top and bottom walls of the shell.

5. A method according to claim 1, further comprising the step of packing gasket material into the lower portions of the spaces between said pile receiving tubes and said piles prior to the introduction of the grouting material into such spaces.

6. In an underwater foundation, in combination, a completely submerged hollow shell having spaced top and bottom walls, upstanding structural members supported by said shell, said shell having a plurality of open ended tubes extending through its top and bottom walls and through the shell from top to bottom thereof, piles driven through said open ended tubes for securing said shell to the bottom and having their heads located within and substantially spaced from the walls of said tubes, a body of settable grouting in the space between said pile heads and tubes, said tubes presenting internal lengthwise acting abutment means for preventing relative longitudinal movement between said tubes and said set grouting composition, and said pile heads presenting external lengthwise acting abutment means for preventing relative movement between said pile heads and said set grouting composition, whereby said shell is interlocked to said pile heads.

7. A combination according to claim 6, said upstanding structural members including members extending inside said shell in spaced relation to its walls, said open ended tubes also presenting endwise acting abutment means inside said shell, and said shell being filled with settable grouting material interlocking said piles, tubes, filling and upstanding structural members into a single unitary body.

8. A foundation construction for use underwater, comprising a prefabricated assembly of supporting structure carried by a watertight initially hollow shell that is completely sub-

merged in use, said shell comprising top, bottom and side walls and open ended tubes extending completely through the shell and sealed into its top and bottom walls to provide for driving of piles through the shell from above the top wall thereof; said shell further comprising means for admitting grouting material to the interior thereof to become set therein; said open ended tubes having inside and outside surfaces presenting lengthwise acting abutment means for interlocking respectively, with said set grouting material and with set cementitious material surrounding the portions of driven piles lying within said tubes; said structure, in place, comprising piles extending out of the lower ends of said open ended tubes and having portions within the tubes presenting endwise acting abutment means spaced from the opposed endwise acting abutment means of the tubes, and having set cementitious material interposed between said portions of the piles and said tubes, whereby said piles are interlocked against endwise movement relative to the set grouting material within the shell irrespective of deterioration of the top or bottom walls of the shell.

9. A foundation construction according to claim 8, in which the supporting structure comprises portions extending within said shell and interlocking with the set grouting material therein, for assuming anchorage of the supporting structure to said piles irrespective of deterioration of the top and side walls of said shell.

10. A foundation construction comprising a submerged hollow form having a watertight external skin with means for introducing of grout therewith, and with open ended pile tubes passing clear through said form from skin to skin thereof and sealed into said skins in watertight fashion, said pile tubes having radially offset walls presenting complimentary longitudinally acting abutment surfaces on the inner and outer sides thereof, piles driven through said pile tubes and having radially offset surfaces lying within said tubes in spaced relation to the radially offset walls thereof, and grouting material filling the spaces between said radially offset surfaces and walls and filling said hollow skin, so that on setting thereof the piles, tubes and form filling constitute one single interlocked structure.
